UNITED STATES PATENT OFFICE.

TALBERT H. PHELPS, OF CHICAGO, ILLINOIS.

ASPHALT-HEATER.

1,150,383.

Specification of Letters Patent. Patented Aug. 17, 1915.

Application filed March 4, 1914. Serial No. 822,422.

To all whom it may concern:

Be it known that I, TALBERT H. PHELPS, a citizen of the United States, residing at Chicago, in the county of Cook and State 5 of Illinois, have invented new and useful Improvements in Asphalt-Heaters, of which the following is a specification.

My invention relates to asphalt heaters, primarily designed for use in repairing or 10 patching old asphalt pavements, the primary object of the invention being to provide a heater of that type having a flame confining hood, wherein provision is made for atomizing the fuel oil, by the action of 15 an atomizing and oxygenizing agent such as steam or air, by which the fuel will be injected into the hood in such a condition as to insure instantaneous and clearly combustion, the production of great heat and 20 the elimination of smoke.

A further object of the invention is to provide a device of this character which may be supported upon a suitable truck for transportation from place to place or attached to a steam roller, as desired.

The invention consists of the features of construction, combination and arrangement of parts herein fully described and claimed, 30 reference being had to the accompanying drawings in which:—

Figure 1 is a side elevation of an asphalt heater embodying my invention. Fig. 2 is a top plan view of the same. Fig. 3 is a vertical longitudinal section through the 35 heater. Fig. 4 is a vertical transverse section.

In carrying my invention into practice, I provide a suitable frame structure, shown in the present instance as comprising parallel bracket arms 1 to which is attached a vertical, transversely disposed yoke 2, reinforced from the arms by braces 3.

The bracket arms 1 are adapted for attachment to a suitable portion of a steam 45 roller, for mounting the heater thereon, or for attaching the device to a suitable truck, allowing the device to be easily transported from place to place. Disposed between the outer ends of the arms, to which the yoke 50 and braces are connected, is a hood or drum 4, made of sheet metal or other suitable material and including a top wall 5, end walls 6 and a back wall 7, the front of the hood and the bottom and front of the drum being

open for the outlet of the flames and to enable the flames to play against the surface of the pavement to be repaired or attached.

Mounted upon the top or cross portion of the yoke or some other suitable support is an oil tank or reservoir 8 having a suitably closed filling opening 9 and a suitably closed opening 10, to which may be attached a connection from an air pump for supplying air under pressure to feed the oil to the burners with the desired pressure. An oil feed pipe 11 leads rearwardly from the bottom of the tank and is connected in rear of the hood by a transverse pipe 12 to a pair of depending discharge pipes 13, which connect with burners or discharge nozzles 14, and extend 70 into the hood through openings 15 in the rear wall thereof. The supply of oil to each burner is controlled by a valve 16, and it will be understood that in practice any number of burners or nozzles and controlling valves 75 therefor may be employed according to the size of the hood and the area of the pavements to be treated. Arranged below and in rear of the transverse pipe 12 is a transverse steam or air supply pipe 17, provided with a 80 central union 18 for connection with a suitable source of steam or air supply. The terminal ends of this pipe 17 communicate with the burners or injectors 14 for the supply of steam or air thereto, and the flow of steam 85 or air to the burner or injectors being controlled by valves 19 in the steam or air supply pipe between the union and the burners or injectors.

In operation, it will be understood that 90 the hood is disposed over a portion of asphalt to be heated, and the valve 16 opened for the supply of fuel, after which the valves 19 are opened for the supply of steam or compressed air. The steam or air blowing through the burners or injectors meets the currents of oil on their flow and atomizes the same, the atomized oil being injected into the hood, so that upon igniting the same an intense flame will be produced, 95 which flame will be confined by the hood to the underlying surface of asphalt to be treated. It has been found in practice that the oil thus atomized when ignited burns 100 cleanly and without the smoke, owing to the fact that the fuel is oxygenated, by which the carbon is raised to the point of incandescence and consumed. By this means the 105

use of complex devices for vaporizing the oil prior to its supply to the burners is avoided, as well as other complicated structures, and at the same time a clear flame and intense heat are produced, minimizing the amount of fuel required and avoiding waste of fuel, while enabling the asphalt surface to be intensely heated and the generation of smoke entirely eliminated. As stated, the device may be mounted upon an independent truck of its own for ready and convenient transportation from place to place, or may be attached to a steam roller or other vehicle for use.

It will be understood that any kind of hydrocarbon or other liquid fuel capable of atomization and of being oxygenated in the manner described may be employed, and that the essence of the invention resides in a means by which an atomization of the oil and its combination with steam or air to effect combustion is secured so as to obtain an intense heat with a consumption of carbon and the consequent elimination of smoke.

It will be observed that by mounting the fuel reservoir above the hood and disposing the fuel supply pipe between the reservoir and hood, the apparatus is not only made compact in character, but a twofold additional advantage is gained, first in that the reservoir and fuel supply pipe are so located as to lie in the path of upward travel of the air heated by the hood, whereby the fuel is kept in a desirable liquid state, thus avoiding any liability of the fuel thickening and becoming torpid in its flow during cold weather, and especially when a low grade hydrocarbon fuel is employed; and secondly, by disposing the feed pipe between the reservoir and hood, the reservoir is heated just enough to keep the fuel liquid and without danger of the formation of explosive gases, while the pipe is heated to a higher degree to raise the temperature of the flowing fuel to adapt it to combine to better advantage with the steam for oxygenation.

I claim:

1. In an asphalt heater, the combination with a frame, of a hood supported by the frame, said hood being open at its base and forward end and embodying side, top and back walls, a yoke extending across the top of the hood, a fuel reservoir tank supported by said yoke, and a fuel supply pipe extending longitudinally between the hood and tank and communicating at its forward end with the latter, perforated injector pipes extending through the rear wall of the hood longitudinally within the latter on opposite sides of the center thereof, cross pipes connecting said fuel supply pipe with the rear ends of the injectors, valves controlling communication between said cross pipes and the injectors, a steam supply pipe, branch pipes connecting said steam supply pipe with the rear ends of the steam injectors in rear of the aforesaid valves, and controlling valves in the said branch pipes.

the injectors, and steam supplying means communicating with the rear ends of the injectors in rear of said valves.

2. In an asphalt heater, the combination with a frame, of a hood supported by the frame, said hood being open at its base and forward end and embodying side, top and back walls, a yoke extending across the top of the hood, a fuel reservoir tank supported by said yoke, and a fuel supply pipe extending longitudinally between the hood and tank and communicating at its forward end with the latter, perforated injector pipes extending through the rear wall of the hood longitudinally within the latter on opposite sides of the center thereof, cross pipes connecting said fuel supply pipe with the rear ends of the injectors, valves controlling communication between said cross pipes and the injectors, a steam supply pipe, branch pipes connecting said steam supply pipe with the rear ends of the steam injectors in rear of the aforesaid valves, and controlling valves in the said branch pipes.

3. In an asphalt heater, the combination of a hood open at its base and forward end and embodying side, top and back walls, a fuel reservoir tank supported above and from said hood, a fuel supply pipe extending longitudinally between the hood and tank and communicating at its forward end with the latter, perforated injector pipes extending through the rear wall of the hood longitudinally within the latter on opposite sides of the center thereof, cross pipes connecting said fuel supply pipe with the rear ends of the injectors, mixing chambers having valves therein connecting and controlling communication between said cross pipes and the injectors, and steam supply means communicating with said mixing chambers and the injectors at a point in rear of said valves.

4. In an asphalt heater, the combination of a hood open at its base and outer end, bracket arms secured to the sides of the hood and extending rearwardly therefrom, a yoke secured to said bracket arms on opposite sides of the hood and having its cross portion extending over the hood and formed with a supporting seat, a fuel supply tank secured in said seat, bracing connections between the sides of the yoke and the bracket arms, injectors disposed on opposite sides of the hood and extending thereinto through the rear wall thereof, a fuel supply pipe fixed to and communicating at its forward end with the reservoir and extending rearwardly between the same and the top of the hood, valved branch pipes leading therefrom to the inlet ends of said injectors, a fluid supply pipe, and branches leading therefrom to said injectors and communicating with the latter in rear of said branch pipes.

5. In an asphalt heater, the combination of a hood, a fuel reservoir extending longitudinally above the hood, a fuel supply pipe disposed longitudinally between the hood and reservoir and communicating with the latter, an injector within the hood, valved mixing and conducting connections between the supply pipe and injector, and valved steam supplying connections com-

municating with the first-named connections. 10

In testimony whereof I affix my signature in presence of two witnesses.

TALBERT H. PHELPS.
